UNITED STATES PATENT OFFICE.

JOSEPH GIUFFRE AND CURTIS W. RICH, OF SAN FRANCISCO, CALIFORNIA.

DISPENSING CIGARETTE CASE.

Application filed May 14, 1921. Serial No. 469,719.

To all whom it may concern:

Be it known that we, JOSEPH GIUFFRE and CURTIS W. RICH, citizens of the United States, residing in the city and county of San Francisco and State of California, have invented a new and useful Improvement in a Dispensing Cigarette Case, of which the following is a specification.

Our invention relates to improvements in dispensing cigarette cases and the like wherein an endless conveyor operates in conjunction with a dispensing member to dispense a cigarette each time the cover is opened.

15 The primary object of our invention is to provide an improved cigarette case adapted to dispense cigarettes.

A further object is to provide a case of the character described arranged to facilitate refilling.

Another object is to provide improved means for moving a cigarette into a position from which it may be readily withdrawn.

25 A still further object of our invention is to provide improved means for moving the dispensing member into an operative position after each operation.

A still further object is to provide an improved construction in a cigarette case of the character described affording positive action and compactness of form.

We accomplish these and other objects by means of the device disclosed in the drawings forming a part of the present specification wherein like characters of reference are used to designate similar parts throughout the said specification and drawings, and in which:

Fig. 1 is a vertical section of our improved cigarette case;

Fig. 2 is a horizontal section taken along the line 2—2 of Fig. 1 in the direction indicated;

Fig. 3 is an enlarged broken detail of the conveyor operating means;

Fig. 4 is an enlarged broken section taken along the line 4—4 of Fig. 1 in the direction indicated; and

Fig. 5 is a broken detail of our improved dispensing means.

Referring to the drawings the numeral 1 is used to designate in general a container having sides 2 hingedly connected along one edge thereof as at 3, as best disclosed in Fig. 2 of the drawing. The container 2 is pro-

vided with a compartment 4 at the bottom thereof and with a cover portion 6 hingedly connected at the top by a suitable hinge 7. The container 1 is likewise provided with top and bottom partitions 8 and 9 and with a centrally disposed vertical partition 11 positioned between the partitions 8 and 9, as best disclosed in Fig. 2 of the drawings.

Shafts 12 and 13 are rotatably mounted between the partitions 8 and 9 adjacent the sides of the partition 11. The shafts 12 and 13 are each provided with a pair of toothed hubs 14. The hubs 14 upon the shaft 12 are arranged vertically opposite the corresponding hubs on the shaft 13.

A pair of endless conveyors 16 are mounted to move about the toothed hubs 14, said conveyors being provided with a plurality of vanes 17 defining compartments 18 each adapted to receive a cigarette 19 therein. The inner surface of the conveyor 16 is preferably provided with serrations 21 adapted to mesh with the toothed hubs 14 to insure a positive movement of the conveyor 16 and vane 17 when the shaft 12 is rotated in a manner hereinafter described.

The upper partition 8 is provided at one end thereof with an aperture 22 of a size adapted to permit the passage of a single cigarette therethrough. The lower partition 9 is provided with a slot 24, one end of which is directly opposite the aperture 22, said slot 24 being of a width less than the diameter of a cigarette. The shaft 13 is made hollow to receive a rod 26 slidably and rotatably mounted therein and extending outwardly at each end thereof. The lower end of the rod 26 is provided with a dispensing member 27. A spring 28 secured within the compartment 4 upon the lower side of the partition 9 has its free end engaging the lower end of the rod 26 and dispensing member 27 in such manner as to normally cause the said dispensing member to be advanced upwardly into the container through the slot 24 as disclosed in dotted lines in Fig. 1 of the drawing.

The cover 6 is provided with a lug 29 adapted to engage the top of the rod 26 and to depress the same when said cover 6 is moved to a closed position, thereby depressing the dispensing member 27 against the tension of the spring 28 to a point slightly below the upper surface of the partition 9.

A spring 31 secured to the lower side of

the partition 9 operates to normally hold the dispensing member 27 in the portion of the slot 24 opposite the aperture 22 of the partition 8. The shaft 12 is provided on its upper end with a ratchet 32 above the partition 8. An arcuate pawl 33 having ratchet teeth 34 adapted to mesh with the teeth of the ratchet 32 is pivotally connected to the cover 6 by a suitable hinge 36 adapted to permit a lateral movement of the pawl 33 with respect to the ratchet 32. A spring 37 operates to normally hold the pawl 33 against the ratchet 32. In this manner, when the cover 6 is open the pawl 33 moves laterally against the tension of the spring 37 to pass the ratchet 32. When the cover 6 is closed, as from the dotted position shown in Fig. 1 of the drawing, the teeth 34 of the pawl 33 engage the ratchet 32 and actuate the same to rotate the shaft 12 thereby advancing the conveyor 16 a corresponding amount.

In operation our invention is as follows:

The sides 2, which are normally held in a closed position by a suitable latch 39, are swung upwardly about the hinge 3 to permit access to the container. A plurality of cigarettes 19 are inserted in a container, each cigarette being placed in a compartment defined by the vanes 17 of the conveyors 16. The sides 2 are then closed and the cover 6 moved about the hinge 7 to a closed position.

A latch 41 is provided for holding the cover 6 in a closed position against the tension of a spring 42 mounted at the hinge 7 to cause the cover to open when the latch 41 is released. The closing of the cover depresses the rod 26 and dispensing member 27 in the manner above described and at the same time moves the conveyor to advance the cigarettes one position.

The compartments 18 are arranged in such a manner as to cause a cigarette 19 to be brought in alignment with the aperture 22 each time the cover 6 is closed. If now the latch 41 is released the cover 6 will be opened by the spring 42 and the cigarette 19 will be pushed upwardly through the aperture 22 by the dispensing member 27 actuated by the spring 28. The upper end of the cigarette 19 will be moved to the position indicated in dotted lines in Fig. 1 of the drawing, where it may be readily grasped for removal. When the cover 6 is again closed the conveyors 16 and cigarettes 19 will be advanced in the manner above described to bring the next succeeding cigarette into alignment with the aperture 22, the movement of said succeeding cigarette displacing the dispensing member 27 against the tension of the spring 31 to the position indicated in dotted lines in Fig. 5 of the drawing. As the cover 6 is moved downwardly the lug 29 is brought against the upper end of the rod 26, further movement of the cover 6 causing the rod 26 and the dispensing member 27, secured to the

bottom thereof, to be depressed to the normal operative position. As soon as the member 27 has cleared the cigarette 19 the spring 31 will cause said member 27 to swing back into alignment with the cigarette next to be dispensed. A successive opening and closing of the cover 6 will bring successive cigarettes into a dispensing position and dispense the same as above described until the contents of the case has been exhausted.

As will be readily seen from the drawings and the above description we have provided a cigarette case of compact form having an attractive appearance and provided with a durable and positive acting mechanism for dispensing cigarettes.

Having thus described our invention what we claim as new and desire to secure by Letters Patent is:

1. A cigarette case comprising a container arranged to receive a plurality of cigarettes; a cover hingedly connected to said container; a cigarette dispensing member slidably and pivotally mounted within the container and arranged to engage one end of a cigarette; a spring mounted within the container in engaging relation with the dispensing member to move said member to dispense said cigarette when the cover is opened; and means actuated by the closing of the cover for moving successive cigarettes into dispensing position after each preceding cigarette has been dispensed.

2. A cigarette case comprising a container arranged to receive a plurality of cigarettes; a cover hingedly connected to said container; a cigarette dispensing member slidably and pivotally mounted within the container and arranged to engage one end of a cigarette; a spring mounted within the container in engaging relation with the dispensing member to move said member to dispense said cigarette when the cover is opened; means actuated by the closing of the cover for moving successive cigarettes into dispensing position after each preceding cigarette has been dispensed; and means for moving the dispensing member into operative engagement with the successive cigarettes.

3. A cigarette case comprising a container arranged to receive a plurality of cigarettes; a cover hingedly connected to said container; a cigarette dispensing member slidably and pivotally mounted within the container and arranged to engage one end of a cigarette; a spring mounted within the container in engaging relation with the dispensing member to move said member to dispense said cigarette when the cover is opened; means actuated by the closing of the cover for moving successive cigarettes into dispensing position after each preceding cigarette has been dispensed; means for

- depressing the dispensing member after each cigarette has been dispensed; and means for pivotally moving said depressed member into operative engagement with the cigarette next to be dispensed.
4. A cigarette case comprising a container arranged to receive a plurality of cigarettes; a cover hingedly connected to said container; a cigarette dispensing member 10 slidably and pivotally mounted within the container and arranged to engage one end of a cigarette; a spring mounted within the container in engaging relation with the dispensing member to move said member to dispense said cigarette when the cover is opened; means actuated by the closing of the cover for moving successive cigarettes into dispensing position after each preceding cigarette has been dispensed; means 15 actuated by the closing of the cover for depressing the dispensing member after each cigarette has been dispensed; and means for pivotally moving said depressed member into operative engagement with the cigarette next to be dispensed.
5. A cigarette case comprising a container; a cover hingedly connected to said container; a conveyor mounted within the container arranged to receive a plurality of cigarettes in spaced relation; dispensing means operatively engaging one end of a cigarette to dispense the same when the cover is opened; and means actuated by the closing of the cover for moving the conveyor to advance the next succeeding cigarette into dispensing position.
6. A cigarette case comprising a container; a cover hingedly connected to said container; an endless conveyor operatively 40 mounted in the container, said conveyor being provided with a plurality of vanes defining compartments arranged to receive a plurality of cigarettes; dispensing means mounted within the container and arranged to engage one end of a cigarette to dispense the same when the cover is opened; and means actuated by the closing of the cover for moving the conveyor to advance the next succeeding cigarette into dispensing 45 position.
7. A cigarette case comprising a container; a cover hingedly connected to the container; a pair of shafts rotatably mounted within the container; an endless conveyor operatively mounted upon said shafts 50 to receive a plurality of cigarettes; dispensing means mounted within the container and engaging one end of a cigarette to dispense the same when the cover is opened; and means connecting one of the shafts and the cover whereby the closing of said cover actuates the conveyor to advance the next succeeding cigarette into dispensing position.
8. A cigarette case comprising a container; a cover hingedly connected to the container; a pair of shafts rotatably mounted within the container; an endless conveyor operatively mounted upon said shafts to receive a plurality of cigarettes; dispensing means mounted within the container and arranged to engage one end of a cigarette to dispense the same when the cover is opened; and a pawl and ratchet connecting one of the shafts with the hingedly connected cover whereby the closing of said cover operates to move the conveyor to advance the next succeeding cigarette into dispensing position.
9. A cigarette case comprising a container; a cover hingedly connected to said container; a pair of shafts rotatably mounted within the container; an endless conveyor operatively mounted upon said shafts and arranged to receive a plurality of cigarettes; dispensing means mounted within the container and arranged to engage one end of a cigarette to dispense the same when the cover is opened; a ratchet secured upon the upper end of one of the shafts; an arcuate pawl mounted upon the cover in engaging relation with the ratchet whereby the closing of the cover after a cigarette has been dispensed operates to move the conveyor to advance the next succeeding cigarette into dispensing position.
10. A cigarette case comprising a container; a cover hingedly connected to the container; a pair of shafts rotatably mounted within the container; an endless conveyor operatively mounted upon the shafts and arranged to receive a plurality of cigarettes; dispensing means mounted within the container and arranged to engage one end of a cigarette to dispense the same when the cover is opened; a ratchet secured upon the upper end of one of the shafts; a pawl pivotally mounted upon the cover; and a spring arranged to permit lateral movement of the pawl to permit the same to pass the ratchet when the cover is opened, and to move said pawl into operative engagement with the ratchet when the cover is closed whereby the conveyor is moved to advance the next succeeding cigarette into a dispensing position after each cigarette is dispensed.
11. A cigarette case comprising a container having its sides hingedly connected along one edge thereof; a cover hingedly connected to the container; an endless conveyor operatively mounted upon the shafts and arranged to receive a plurality of cigarettes; dispensing means mounted within the container and arranged to engage one end of a cigarette to dispense the same when the cover is opened; a ratchet secured upon the upper end of one of the shafts; a pawl pivotally mounted upon the cover; and a spring arranged to permit lateral movement of the pawl to permit the same to pass the ratchet when the cover is closed whereby the conveyor is moved to advance the next succeeding cigarette into a dispensing position.

ratchet when the cover is opened, and to move said pawl into operative engagement with the ratchet when the cover is closed whereby the conveyor is moved to advance the next succeeding cigarette into a dispensing position after each cigarette is dispensed.

12. A cigarette case comprising a container; a cover hingedly connected to said container; an endless conveyor operatively mounted within the container and arranged to receive a plurality of cigarettes; a dispensing member slidably and pivotally mounted within the container and arranged to engage one end of a cigarette; means for returning said dispensing member to an operative position when the cover is closed; and a pawl and ratchet operatively connecting the endless conveyor and the cover whereby the closing of said cover actuates said conveyor to move the next succeeding cigarette into dispensing position.

13. A cigarette case comprising a con-

tainer; a cover hingedly connected to the container; a pair of shafts rotatably mounted within the container; an endless conveyor operatively mounted upon said shafts and arranged to receive a plurality of cigarettes; a spring actuated dispensing member slidably and pivotally mounted within the container and arranged to engage one end of a cigarette to dispense the same when the cover is opened; means for returning said dispensing member to an operative position when the cover is closed after said cigarette has been dispensed; a ratchet secured to one end of one of the shafts; an arcuate pawl pivotally mounted upon the cover in engaging relation with the ratchet whereby the closing of said cover after a cigarette has been dispensed operated to move the conveyor to advance the next succeeding cigarette into dispensing position.

In witness whereof we hereunto set our signatures.

JOSEPH GIUFFRE.
CURTIS W. RICH.
